John E. Jackson
his Attorney.

UNITED STATES PATENT OFFICE

2,204,559

ROAD GUARD

Carl C. Ahles, Albany, N. Y.

Original application July 8, 1935, Serial No. 30,374.
Divided and this application July 20, 1939,
Serial No. 285,633

2 Claims. (Cl. 256—13.1)

The present invention, which is a division of my application, Serial No. 30,374, filed July 8, 1935, relates to road guards. For a complete understanding of the invention, reference is made to the following description, the accompanying drawing and the appended claims.

The present invention relates to highway guards of the general type disclosed in my above identified application, the particular feature of this divisional application being directed to improvements in the mounting for the flexible guard elements. For a complete disclosure, reference is made to the accompanying drawing, in which:

Figure 1 is a front elevation illustrative of a guard rail embodying the present invention; and

Figure 2 is a detail on line II—II of Figure 1.

Referring more particularly to the drawing, the guard rail of the present invention comprises a plurality of flexible elements, such as indicated at A which in the case illustrated may be regarded as wire ropes, strands or cables. These cables extend past a series of posts 81 suitably anchored in the ground. The particular feature of the present invention relates to a novel form of mounting for the flexible elements A best shown in Figure 2.

Referring to Figure 2, the post carries a piece of flat spring metal 82 formed into a series of successively reversed loops, this piece being mounted

by the post, through the medium of bolts 83, in alinement therewith and so that the loops extend therefrom. A series of wire ropes A extend transversely past the post 81 and are fastened to the outside of those of the loops that extend away from the post, such fastening being effected by means of hook-bolts 84. A stay-bolt 85 is illustrated in dotted lines, since in some instances it may be best to pass such a stay-bolt transversely through the various loops formed by the piece 82. 10

I claim:

1. A guard rail including the combination of a post, a piece of flat spring metal formed into a series of successively reversed loops, said piece being mounted by said post in alinement therewith and so that said loops extend therefrom, and a series of strands extending transversely past said post and fastened to the outsides of those of said loops that extend away from said post. 15

2. A guard rail including the combination of a post, a piece of flat spring metal formed into a series of successively reversed loops, said piece being mounted by said post in alinement therewith and so that said loops extend therefrom, and a flexible vehicle guard member and means 20 for securing the same to those loops which extend away from said post. 25

CARL C. AHLES.
